UNITED STATES PATENT OFFICE.

EDGAR M. CORBETT, OF PATERSON, NEW JERSEY.

DESIGN FOR RIBBON.

No. 38,581.

Specification for Design.

Patented May 21, 1907.

Application filed April 17, 1907. Serial No. 368,799. Term of patent 14 years.

To all whom it may concern:

Be it known that I, EDGAR M. CORBETT, a citizen of the United States, and a resident of Paterson, in the county of Passaic and State of New Jersey, have invented a new, original, and ornamental Design for Ribbons, reference being had to the accompanying drawing, in which the figure is a plan view of a strip of the ribbon, showing my new design.

I claim:

The ornamental design for a ribbon as shown.

EDGAR M. CORBETT.
